Primary Examiner — Mitchell I. Siegel*(74) Attorney, Agent, or Firm* — Finnegan, Henderson Farabow, Garrett & Dunner, LLP(57) **CLAIM**

The ornamental design of a water ride, as shown and described.

DESCRIPTION

FIG. 1 is a perspective view of a water ride showing my new design;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The broken lines shown in the figures are for the purpose of illustrating portions of the water ride that form no part of the claimed design.
